FUR NAILING PINCHER

Abraham Lipson, New York, N. Y.

Application March 23, 1939, Serial No. 263,725

4 Claims. (Cl. 1—45.5)

This invention relates generally to the art of the treatment of furs and more particularly to improvements to what are known in the art as fur nailing pinchers.

The invention disclosed in the present application embodies certain improvements over that disclosed in my co-pending application Ser. No. 245,666, filed December 14, 1938, as is set forth in greater particularity hereinbelow.

In the preparation of the various pelts used in the fur art for subsequent inclusion into garments which are usually made up of a plurality of these pelts which are sewn together, it is the usual practice to stretch and shape these pelts prior to sewing them together, by spreading them to the requisite shape on a board and nailing them in place until they set in the desired configuration.

Where the size of the pelt is small or for the purpose of fur pattern, the pelt is sub-divided, the operation of stretching and shaping the pelt and nailing it to the board may take considerable time and consequently raise the cost of the finished garment. As for example, the average mink coat requires from 1,800 to 2,500 pins or nails. That this is a tedious and difficult process may be realized because frequently the distance between the rows of pins which fasten the edges of the skins to the board may be as small as 1 to 2 inches.

It is an object of the present invention to so improve the known fur nailing pinchers presently used in the art so that the skilled furrier's dexterity and speed is increased and the apprentice furrier is enabled, after a short training period to reach the speed of men more skilled and with far greater experience. Heretofore the operator in working on the stretching and shaping board usually placed a small pile of nails or pins at a point remote from the actual point on the board which he was engaged in stretching a skin. With one edge of the skin already fastened to the board by the pins the other edge of the skin (assuming a right handed person) is fed into the jaws of the pincher, and the pincher is compressed and pulled by the right hand. It is then necessary for the left hand to secure a pin from the pile and return to the point where the pincher jaws have held the skin. The pin is then inserted through the skin into the board by the left hand and is then driven into the board by means of striking the same with the pinchers after they have been released from the edge of the fur. Some workers may attempt to keep a supply of the nails or pins in their left hand but this in-

terferes with the dexterity of the left hand in shaping and spreading the pelt. In accordance with the present invention, this process is vastly improved as will be more fully discussed below.

5 Another object herein lies in the provision of means in combination with a fur nailing pincher which are adapted to hold a plurality of pins or nails on the pinchers and from which they may be manually fed with great speed.

10 Another object herein lies in the provision of novel structure for holding and advancing the pins or nails used in fur stretching and which is simple in construction so that the same may be readily adapted to fur pinchers already in use or 15 may be incorporated with the same when they are manufactured.

A still further object herein lies in the provision of pin holding and advancing structure in combination with a fur nailing pincher which 20 permits adjustment to suit the habits of various operators.

25 A further object of the present invention lies in the pin holding and advancing structure being of streamlined shape and being extremely light in weight so that the natural balance of the pinchers is not disturbed.

The novel pin holding and advancing structure herein is of simple construction so that the same may be manufactured at relatively low cost 30 and may be readily applied to all fur pinchers in use.

In accordance with the present invention as compared with that disclosed in my co-pending application referred to above, the number of pins 35 which may be held on the fur nailing pinchers at one time, the facility of operation, and adaptability of the parts to suit various users is greatly increased.

These objects and further features and advantages will more fully appear in the progress of this disclosure and as pointed out in the appended claims.

In the drawing forming an important part of this disclosure and in which similar reference characters designate corresponding parts throughout the several views:

Fig. 1 is a left side elevational view of a known fur nailing pincher which has been altered to adapt it for receiving the pin holding and advancing means and maintaining same in operative position. The movement of the jaws and handles of the pincher is indicated by dot-dash lines.

Fig. 2 is a view taken similarly to Fig. 1 showing a right side elevational view of the fur nail-

ing pinchers illustrated in Fig. 1 with the pin holding and advancing means in place, and in the retracted position thereof.

Fig. 3 is a plan view of Fig. 2 with the handle end of the fur nailing pinchers broken away. In this view a few pins are shown for the purpose of example, while in normal use the pin holding means holds a considerably greater number of pins, the same has not been illustrated for purpose of clarity in the drawing.

Fig. 4 is a front elevational view of the pin holding and advancing device as removed from the fur nailing pinchers, as would be seen from the right side of Fig. 3.

Fig. 5 is a rear elevational view of the pin holding and advancing device as removed from the fur nailing pinchers, as would be seen from the left side of Fig. 3.

Fig. 6 is a fragmentary central vertical sectional view as seen from the plane 6-6 on Fig. 3. In this view the pin holding advancing device is in the extended or advancing position thereof, while the retracted position is illustrated in dot-dash lines.

Fig. 7 is a horizontal sectional view as seen from the plane 7-7 on Fig. 4. In this view the extended or advancing position of the pin holding device is indicated in dot-dash lines.

Fig. 8 is a plan view of a substitute operating handle adapted for use by operators having medium sized fingers or one who desires to hold the fur nailing pinchers at a point nearer the ends of the handles of said pinchers.

Fig. 9 is a view taken similarly to Fig. 8 and showing a still longer operating handle.

Fig. 10 is a central vertical sectional view of the replaceable magnetic element as removed from the pin holding means. This magnetic element is also seen in Figs. 3 and 6.

Fig. 11 is a side elevational view of a second form of the replaceable magnetic element.

Fig. 12 is a central vertical sectional view of a third form of the replaceable magnetic element as removed from the pin holding means.

The fur nailing pinchers generally indicated by numeral 10 are of plier like construction having members 11 and 12 which are pivotally interconnected by means of the rivet pin 13. The member 11 comprises a lower jaw 14, a central portion 15 and a palm engaging handle 16. The member 12 comprises an upper jaw 17, a central portion 18 and a finger engaging handle 19. The jaws 17 and 14 adjacent the tips 20 and 21 thereof are provided on the inner opposed surfaces thereof with corrugations 22 and 23, while the outer face of the lower jaw 14 adjacent the tip 21 is provided with pin head engaging corrugations 24. The jaw 17 is provided with orifices 25 and 26, the lower entrances of which are suitably countersunk (see Fig. 1).

The pin holding and advancing device 30 includes generally the pin holding means 31 and the advancing and mounting means 32.

The advancing and mounting means 32 comprises a base plate 33 which is generally L-shaped including an upper jaw engaging plate 34 and two upwardly and outwardly extending integral ears 35 (see Fig. 5).

The plate 34 and ears 35 are preferably composed of aluminum, duraluminum or other light relatively non-magnetic material. The under surface of the plate 33 is shaped to conform to the upper surface of the upper jaw 17 and is secured thereto preferably by means of two flat head machine screws 40 and 41 which penetrate

the orifices 25 and 26 respectively and engage correspondingly disposed threaded orifices in the base plate 33. The ears 35 are provided with threaded orifices 60 which support horizontally disposed guide arms 61. The guide arms 61 are preferably formed by rods 62 circular in cross section having their rear ends 63 reduced in size and threaded, and engaged within the orifices 60, and having their forward ends provided with slotted integral heads 64. The central portion of the rods 62 thus forms the long unthreaded shank of a screw and the rear edge of said portion forms a shoulder which abuts against the forward vertical surfaces of the ears 35 thereby properly aligning the guide arms so that they are parallel and spaced from each other and from the base plate 33. The shoulder formed at the rear end of the central portion of the rods 62 also serves to strengthen the connection of these rods to the ears 35.

Turning now to the pin holding means 31, there is seen a pin container, cup or reservoir 65, the configuration of which is best seen in Figs. 3 to 6 inclusive. The upper portion thereof comprises generally a shallow pan 66 preferably having parallel and longitudinally disposed side walls 67 and opposed semi-circular ends 68 and 69.

The bottom portion of the pan 66 is integral with a pan base 70 which is generally rectangular in shape and somewhat shorter than the longest dimension of the pan 66.

The function of the pan base 70 is to support the pan slidably on the guide arms 61 and also to removably contain the replaceable magnetic element 47. For this reason, the combined pan 66 and its integral base are cut away wherever possible to reduce the weight thereof without sacrificing any material which is requisite for the strength of the device. This configuration is clearly illustrated in the drawings and includes the rounded ends 71 and 72, oppositely and longitudinally disposed grooves 73 and 74.

The lower portion of the pan 66 and the upper portion of the pan base 70 is provided with a horizontally and longitudinally disposed bore 75 having a smooth forward portion 76 and a threaded rear portion 77, rear portion 77 continuing to form an opening 78 in the rear of the pan 66 and the pan base 70 (see Fig. 5).

The magnetic element 47 is substantially cylindrical in cross section and of a diameter substantially equal to the internal diameter of the bore 75 so that the same is slidable therealong. The upper surface 79 of the magnetic element 47 is preferably flat so that a considerably more effective surface of the magnetic element 47 is exposed in the bottom of the shallow pan 66. The threaded rear portion 77 of the base 75 is adapted to receive a threaded plug 80 which removably secures a magnetic element 47 in place within the forward portion 76 of the bore 75. The rear end of the plug 80 is provided with a slot 81' to facilitate the insertion or removal of the plug 80 by means of a screw driver.

The pan base 70 is provided with two spaced parallel bores 82 and 83 which extend into the pan base from the forward end thereof to a point slightly forward of the rear face 84 of the pan base 70. Short counter bores produce the inwardly extending integral annular shoulders 85 and 86. The internal diameter of the counter bores producing the shoulders 85, 86, is substantially equal to the diameter of the central portions 62 of the guide arms 61; while the internal

diameter of the bores 82 and 83 is substantially equal to the external diameter of the slotted heads 64 of the rods 62.

From a perusal of Fig. 7 it being understood that sufficient clearance of the moving parts with relation to each other is provided, it may be seen that the pan base 70 is slideable along the two guide arms 61. The shoulders 85 serve to limit the forward movement of the pan base by compressing the spring against the under or inner surfaces of the slotted heads 64. The rear face 84 of pan base 70 reaches a rear limit by striking against the forward vertical surfaces of the ears 35. The pan base 70 is normally resiliently maintained in the rear or retracted position thereof by the action of expansive coil springs 87 which encircle the central portions of the guide arms 61 and are disposed within the space existing between the outer surface of the rods 62 and the inner surfaces of the bores 82 and 83.

Since the pan base 70 together with the pan 66 is maintained in position by the guide arms 61 it may be seen that the pan and base may be replaced or springs of different tension may be substituted merely by disengaging the two threaded ends 63 of the guide arms 61. This operation may be readily performed by means of a screw driver engaging the slotted heads 64.

The groove 13 is shortened in order to accommodate a recess 90 in the side of the pan 66 and the base 70 and this recess is provided with a downwardly extending operating arm 91 which is secured in place by a flat head machine screw 92 which engages the pan base adjacent thereto. The lower end of the arm 91 extends outwardly at 93 and is provided with a longitudinally directed threaded orifice 94. The orifice 94 is adapted to receive the threaded forward end of a shank 95 having an integral operating button 96.

Figs. 8 and 9 show shanks 95' and 95'' respectively having operating buttons 99' and 96'' and threaded ends 97' and 97''. It is a simple screwing operation to remove the shank 95 from the orifice 94 and substitute therefor either of the shanks 95' or 95'' thus allowing an adjustment to suit the requirements or fancy of the individual operator manipulating the present fur nailling pinchers. While three sizes are shown on the drawing, it is obvious that other sizes may be incorporated.

In Fig. 11 showing a second type of magnetic element 47' the upper surface thereof in addition to being flattened as at 79' is also provided with a central depression 98'. This depression causes the formation of two opposite poles 99' and 100'. A concentration of magnetic flux occurs between these poles and the pins or nails for which the present device is especially adapted, act as keepers for the magnetic element.

Fig. 12 discloses a third type of magnetic element in which the magnetic element 47'' is provided with a longitudinally disposed groove or furrow 98'' in the top surface thereof and similarly with the device of Fig. 11, a concentration of magnetic field occurs between the two longitudinally disposed poles 99'' and 100''.

The magnetic elements 47, 47' and 47'' are preferably composed of material having high magnetic strength, as for example, nickel-steel-cobalt alloy known in the magnetism art.

It is desirable that all of the parts described above with the exception of the magnetic elements, be composed of relatively non-magnetic

material such as aluminum, aluminum alloys or brass.

Operation

- The pinchers are dipped into a supply of nails or pins 57 and the magnetic element 47, 47' or 47'' causes a plurality of these to become attached to itself. The forward rounded front end of the shallow pan 66 serves as a scoop and since the same has a relatively thin curved edge, it facilitates the easy insertion of the entire pan 66 as well as the adjacent parts into the supply of nails or pins. Since because of the relatively small size of the magnet, a great number of nails or pins cannot be attached to it directly, the present device takes advantage of the magnetism temporarily induced into these nails or pins which are directly in contact with the magnet, and utilizes the direct contact nails as temporary magnets to hold against them additional nails.
- 20 The outer or additional nails which are relatively distant from the magnetic element itself are held by progressively weaker magnetic attraction. This is compensated for, however, in that the bordering upper surface of the shallow pan 66 aids in the support of the outermost nails against the attraction of gravity. Furthermore, the inner surface of the shallow pan adjacent the edge thereof by reason of their sloping direction causes the nails or pins to roll toward the magnetic element. The net result of all of this is that a considerably greater number of nails or pins may be held directly or indirectly by the magnetic element through the use of applicant's present invention.
- 35 Assuming the operator to be right handed and one edge of the skin to be fastened by a previous nailing operation, the operator shapes the skin and feeds it into the jaws 17 and 14 with his left hand at the same time stretching the skin
- 40 by pressing the jaws 17 and 14 together and by pulling the pinchers 18 away from the point at which the skin has been previously fastened. The palm of the right hand engages the handle 16 while the fingers engage the handle 19. The little finger may act upon the portion 58 of the handle 19 for opening the jaws. The index finger then engages the button 96, and as the index finger is straightened the entire assembly including the shallow pan 66, the pan base 70, the magnetic element 47, the threaded plug 80 which serves as a retaining member, and the operating arm 91 are advanced forwardly to a position indicated by the full lines in Fig. 6 of the dot-dash lines in Fig. 7. This brings the pins 57 forwardly so that they lie directly over the tip 20 at which point the thumb and the index finger or other finger of the left hand may grasp one of these pins without the necessity of raising the left hand from the surface of the skin being treated. The pin
- 55 so grasped may then be inserted through the skin and started into the board (not shown). The index finger of the right hand is relaxed allowing the mechanism 30 to become retracted by the action of the springs 87. The jaws 17 and 14 are separated and the edge of the skin is released from the corrugations 22 and 23. The corrugated surface 24 and the forward portion of the tip 21 is then used as a hammer to drive the pin securely into the board. Because of the relatively light weight of the pins 27 and the high magnetic strength of the element 47, together with the peculiar construction of the adjacent parts as hereinabove set forth, the pins remaining within the shallow pan 66 are not jarred loose therefrom by said hammer blow, an
- 60
- 65
- 70
- 75

amount sufficient to cause them to fall from the pan. If the hammer blow should be sufficiently strong to jar the pins loose from actual contact with the magnetic element, the sloping internal walls of the shallow pan and the general configuration thereof will cause the pins to roll or move by the action of gravity to a position in which they are securely held by the action of the magnetic element.

In order to make adjustments to suit the convenience, or size of pins, or operating habits of the operator the threaded plug 80 may be removed and the magnetic element may be removed for the purpose of remagnetization, if such is necessary, or the magnetic element may have substituted for itself another magnetic element of different size or configuration. As will be obvious, the arm 91 and the button 96 may be disposed on the opposite side of the pincher when it is intended that the tool be used in the left hand.

It may be thus seen that I have provided a novel combination pin holding and advancing fur nailing pincher which is simple in construction, economical to manufacture, efficient and serviceable and which marks a definite improvement in the art of treating furs, making the general cost of producing sewn fur garments cheaper by reason of the time saving factor which it provides.

I wish it to be understood that I do not desire to be limited to the exact details of construction shown and described, for obvious modifications will occur to a person skilled in the art.

I claim:

1. Fur nailing pinchers comprising: magnetic pin holding means associated with one of the jaws of said pinchers and adapted for rectilinear movement longitudinally of the jaw and pinchers, said magnetic means including a pan and a magnetic element removably disposed in the base of said pan; manually operable slidably mounted means to advance said magnetic means along said jaw, and resilient means acting to move the magnetic means to the retracted position thereof whereby said magnetic means may be maintained normally in the retracted position thereof at a point removed from the operating tips of said

pinchers and may be manually shifted to the advanced position thereof adjacent said tips.

2. In a fur nailing pincher: a base plate adapted to engage the upper jaw of said pincher, said plate having an upwardly extending integral ear; a horizontally disposed guide arm supported at one end thereof by said ear; a pin container in the form of a shallow pan having a longitudinally disposed bore penetrated by said guide arm and slidably therealong to a retracted position at a point removed from the operating tips of said pinchers or to an advanced position at a point adjacent said tips; spring means to normally maintain said pan in the retracted position thereof; and a downwardly extending operating arm connected to said jaw whereby the pan may be manually shifted to the advanced position thereof.

3. Fur nailing pinchers comprising: pin holding means including a pan having an open top associated with one of the jaws of said pinchers and adapted for rectilinear movement longitudinally of the jaw and pinchers, and means to reciprocate said pin holding means along the said jaw whereby said pin holding means may be maintained in a retracted position thereof at a point removed from the operating tips of said pinchers and in the advanced position thereof may be moved to a point adjacent said tips.

4. In a fur nailing pincher: a base plate adapted to engage the upper jaw of said pincher, said plate having an upwardly extending integral ear; a horizontally disposed guide arm supported at one end thereof by said ear; a pin container in the form of a shallow pan having a longitudinally disposed bore penetrated by said guide arm and slidably therealong to a retracted position at a point removed from the operating tips of said pinchers or to an advanced position at a point adjacent said tips; spring means to normally maintain said pan in the retracted position thereof; a downwardly extending operating arm connected to said jaw whereby the pan may be manually shifted to the advanced position thereof; a magnet; and a secondary bore in the lower portion of said pan adapted to replaceably receive said magnet.

ABRAHAM LIPSON.
